WARREN ROWELL, OF NEW YORK, N. Y., ASSIGNOR TO HIMSELF
AND JOHN HECKER, OF SAME PLACE.

Letters Patent No. 84,305, dated November 24, 1868.

IMPROVEMENT IN MOULDING GEAR-WHEELS.

The Schedule referred to in these Letters Patent and making part of the same

To all whom it may concern:

Be it known that I, WARREN ROWELL, of the city, county, and State of New York, have invented a new and useful Improvement in the Method of Moulding Double-Gear Wheels; and I hereby declare that the following is a full and exact description of my improved method, reference being had to the accompanying drawings, forming a part of this specification, in which—

Figure 2 is a face view of one side of the plate, with the patterns attached thereto.

Figure 1 is an elevation.

Figure 3 is a section through the line X X.

Figure A is a perspective view of the castings when completed.

Similar letters of reference indicate corresponding parts in all the figures.

The castings which I produce by my method are the peculiar castings described in my patent dated September 3, 1867, for use in gearing the rolls of clothes-wringing machines. It is impossible to cast these by any ordinary process without the aid of a core. My invention casts them without the aid of a core.

The difficulty lies in the production of the groove which extends around the wheel between the two series of teeth. There is a web or ring on the casting, which extends out to or near the pitch-line of the teeth. There is no difficulty in producing this. The difficulty all lies in providing for the clear space exterior to this, which I have denominated a groove.

As these wheels have been heretofore cast, this groove has been produced by inserting a core in the form of a ring, having an internal diameter equal to the pitch-line of the gear, and an exterior diameter, something greater than the extreme points of the teeth, it being understood, of course, that the portion extending beyond the teeth is for the purpose of taking hold in the sand of the mould, to hold the inner and useful portion of the core in place.

I have discovered that by skilfully dividing such core into parts, and attaching the parts alternately, first to the one part of the mould, and then to the other, the core thus divided will perform the same as usual. And I have discovered that the core thus divided gives a form of the parts which may be moulded in green sand entirely, without involving any more labor or skill than that possessed by the ordinary moulder. In other words, I can by this means make the core, if it so be called, in green sand, as a part of the ordinary green-sand mould, care being taken, in forming the pattern, to make the alternate divisions of the part corresponding to the core, and which I call the green-sand core, carefully adapted to each other, so as to match perfectly together.

I have made, also, some improvements in the means of carrying out my invention.

It may be said that my invention consists in certain novel means of causing the spaces between the teeth, in the direction of the line of the axes of the wheels, to be produced without the aid of, and thereby saving the labor of making a dry-sand core, so that when the two sides of the plate or plates having corresponding sides have been moulded on, and the two moulds put together, the casting produced shall be the same as that now produced by the dry-sand core.

In order to do this, I recess the plate to the depth of one-half the usual dry-sand core, then take a ring, shown in section at O, fig. 3, that shall fit the recess in the plate, and rise above the plate the same height, or nearly, and divide it into twice the number of parts as there are teeth in the wheel.

I place in the recess under each tooth in the wheel, shown in plan, fig. 2, a', a'', &c., one of the said parts, care being taken to have each portion of the ring so bevelled that it shall leave the sand readily.

As both sides of the plate, with the pattern attached, or the two sides of corresponding plates are nearly alike, only one side of the plate and one-half pattern are shown in the drawings.

By nicely adjusting the plate to the flask in which the sand is moulded, and the pattern or half pattern properly adjusted to the plate, one plate is sufficient to mould the two sides of the flask by turning over the plate.

In order to allow for a lateral motion of the pattern in regard to the plate, I leave a space between the plate and pattern, shown at e' e'', fig. 1, and place therein an elastic material, so that on rapping the plate on its alternate sides and ends, the patterns, on being moulded, are loosened in the sand, and thereby are the more readily withdrawn without marring the sand, the elastic material fitting so close as not to allow the sand to get in the joint, but still not having lateral pressure enough to overcome the weight of the pattern, the pattern being attached to the plate in any suitable manner to allow of this lateral motion.

It may, however, be convenient to have the patterns so attached to the plate that in order to withdraw them from the sand the pattern will leave the plate on being moulded, and remain in the sand on lifting off the plate, and then be withdrawn. In this case the elastic material may be dispensed with, and the pattern loosened in the sand, by rapping, as is ordinarily done.

As the circumstance of flasks and sand is so well known to moulders, it is not necessarily shown.

In order to diminish the cost of patterns when more than one is wanted, I make a suitable metal pattern, with a portion of the plate attached, (a circular portion preferred,) and multiply them by the electrotype-process, and recess the main moulding-plate, as shown in the dotted line n n, fig. 1 and fig. 3, and place the

electrotype patterns in the said recesses. By this means from one to ten or more wheels can be moulded at one time.

What I claim as my invention, and desire to secure by Letters Patent, is—

1. Moulding my double-gear wheel A with the groove between the two series of teeth, by in effect dividing the core into parts or steps, and mounting the parts alternately in the opposite flasks, and forming them of

green sand at the same time the main parts are formed, substantially as for the purposes herein set forth.

2. The introduction of an elastic substance between the pattern and plate, as described.

WARREN ROWELL.
